CLAIM

I claim the ornamental design for a basin, as shown and described.

DESCRIPTION

FIG. 1 is a front perspective view of a first embodiment of a basin showing my new design;

FIG. 2 is a rear perspective view of the basin of FIG. 1;

FIG. 3 is a front view of the basin of FIG. 1;

FIG. 4 is a rear view of the basin of FIG. 1;

FIG. 5 is a top view of the basin of FIG. 1;

FIG. 6 is a bottom view of the basin of FIG. 1;

FIG. 7 is a left side view of the basin of FIG. 1;

FIG. 8 is a right side view of the basin of FIG. 1;

FIG. 9 is a front perspective view of a second embodiment of the basin;

FIG. 10 is a rear perspective view of the basin of FIG. 9;

FIG. 11 is a front view of the basin of FIG. 9;

FIG. 12 is a rear view of the basin of FIG. 9;

FIG. 13 is a top view of the basin of FIG. 9;

FIG. 14 is a bottom view of the basin of FIG. 9;

FIG. 15 is a left side view of the basin of FIG. 9; and,

FIG. 16 is a right side view of the basin of FIG. 9.

The broken lines in the drawing views illustrate portions of the basin that form no part of the claimed design. The shade lines in the drawing views show contour and not surface ornamentation of the basin.
